UNITED STATES PATENT OFFICE.

BLAISE J. NUCCIO, OF NEW ORLEANS, LOUISIANA.

BUILDING-COOLING SYSTEM.

Application filed September 3, 1927. Serial No. 217,365.

This invention relates to new and useful improvements in ventilating systems for theatres, auditoriums, and other buildings and has more particular reference to means whereby cold air is forced to circulate throughout the entire interior of the building with the end in view of having a large attendance within the theatre, auditorium or the like in warm weather.

10 A most important object of the present invention is to provide such a cooling system that may be installed during or after the construction of the building and this without great expenditure and wherein the device

15 may be operated at minimum cost.

With the foregoing and other objects in view as the nature of the invention will be better understood, the same comprises the novel form, combination and arrangement of 20 parts hereinafter more fully described, shown in the accompanying drawings and claimed.

Figure 1 is a fragmentary section through a theatre, auditorium or the like equipped 25 with my improved cooling system.

Figure 2 is a diagrammatic section through certain structural features of the system.

Figure 3 is a horizontal section through 30 the water cooling chamber taken substantially upon the line 3—3 of Figure 2.

Figure 4 is a perspective of the water discharge pipe, and

Figure 5 is a fragmentary perspective partially in cross section of a water collecting trough that comprises an essential feature of the invention.

Now having particular reference to the drawings A designates a theatre, auditorium 40 or the like constructed to provide the usual orchestra B, balcony C and stage D.

Furthermore, the building is so constructed as to provide in back of the balcony C a room E within which the main structural 45 units of the present cooling system is disposed.

In carrying out the present invention there is arranged horizontally between the outer wall of the building and the inner wall 50 of the room E an air pipe 5, the inner end of

which is bent upwardly within the balcony area to provide a discharge nozzle 6. As clearly disclosed in Figure 1 this pipe 5 has communication with the atmosphere at the exterior of the building. Arranged vertically within this pipe 5 is an air deflecting drill 60 7 consisting of spaced horizontally arranged vanes that are slightly inclined in a transverse direction to cause the air to flow in an upward direction. Arranged within this pipe 5 at the lower end of the nozzle 6 is an 65 electrically operated fan 8 that serves to suck the air into the pipe and to discharge the same through the nozzle 6.

Located within the room E is a water cooling chamber 9 preferably consisting of a receptacle having a removable lid 10 and within which is to be disposed a quantity of ice or other cooling medium 11. Furthermore within this container is a water coil 12 that extends through the container and that has 70 communication at its upper end with a transversely extending trough 13 formed integrally with the bottom wall of the horizontal air inlet pipe 5. This coil communicates at its lower end with an electrically operated 75 circulating pump 14 the exhaust of which has communication with a horizontally arranged water discharge pipe 15 within the pipe 5 directly above the trough 13, and this through the medium of a connecting pipe 16. 80 85

Obviously during the operation of the device there will be a continuous flow of water from the coil into the pipe 5, the water being discharged from small openings in the bottom of the horizontal pipe 15 whereby 90 the water will flow in a plurality of streams through which the air is sucked by reason of the fan 8 whereupon the same will become chilled before being injected into the interior of the building. The water flowing 95 from the pipe 15 will be caught in the trough 13 and thence led into the coil 12 whereupon it will again be chilled.

It is to be understood that I do not desire to be limited to the specific structural features, nor to any particular manner of chilling the water, as changes may be made therein without affecting the spirit and scope of the appended claim. 100

Having thus described the invention, what I claim as new and desire to secure by Letters Patent is:—

5 In a ventilating device for buildings, an air pipe arranged through a wall of a building adjacent the roof thereof and having communication with the atmosphere and

with the interior of the building, a constricted nozzle at the inner end of the pipe, said nozzle being disposed inclinedly toward the roof, and a suction fan at the lower end of said nozzle.

In testimony whereof I affix my signature.

BLAISE J. NUCCIO.
